MIXING DRUM

Andy W. Cutler, St. Joseph, Mo.

Application October 20, 1937, Serial No. 170,044

4 Claims. (Cl. 259—164)

My invention relates to mixing drums which may be employed to advantage in mixing various materials, such, for instance, as those employed for raising depressions in concrete highways to their original level by being forced into such depressions through holes cut in the concrete slab.

The mixing device is preferably rendered portable by mounting it upon a traveling truck carrying appropriate equipment for forcing the plastic mixture into the depressions as the plastic mixture is discharged from the mixing drum.

In order that the invention may be fully understood, reference will now be had to the accompanying drawings, in which—

15 Fig. 1 is a side elevation of the machine.

Fig. 2 is a broken vertical longitudinal section of the mixing drum and associated parts.

Referring in detail to the different parts, 20 2 designates a suitable traveling truck provided with oppositely-disposed antifriction rollers 4 upon which the mixing drum 6 is rotatably mounted. The mixing drum 6 is reinforced with bands 8 which travel upon the rollers 4 and cooperate with the flanges 5 of the latter in restraining the drum from longitudinal movement. Flanged rollers 9, engaging the bands 8, cooperate with the rollers 4 in holding the drum 6 in place. The mixing drum 6 is driven by an external ring gear 12 fixed thereon and intermeshing with a pinion 14 fixed upon a shaft 16 provided at its forward end with a pulley 18 driven from a pulley 20 by means of an endless belt 22. The drive pulley 20 is fixed upon a shaft 24 which may be connected by any suitable clutch means to the shaft of an engine 26 mounted upon the forward portion of the truck 2.

Referring now more particularly to Fig. 2 it will be seen that the interior of the drum 6 is divided into compartments 28 and 30 by a partition 32 having a central opening 34 in axial alignment with openings 36 and 38 in the respective ends of the drum. Dirt taken from the roadside, or adjacent territory, is fed into the first compartment 28 with a receiving chute 40 which extends through the opening 36. To provide a batch of plastic mixture water is added from a tank 42 having a valve controlled discharge pipe 44 extending into the first compartment 28 through the opening 36. A suitable number of spiral-like blades 46 are fixed within the first compartment 28 to thoroughly mix the substances therein and move the mixture towards the opening 34 in the partition 32. Each alternate blade 46 is spaced 55 inwardly from the inner surface of the drum 6

to render the blades more effective in agitating and mixing the substances. The blade ends 48 adjoin the partition 32 and are arranged in parallelism with the axis of the drum to prevent them from forcing the mixture into the second compartment 30 through the opening 34 prematurely. The parallel ends 48 are assisted in retaining the mixture in the first compartment 28 by means of an inclined deflector chute 50 having its upper end extending into the second compartment 30 and its lower end projecting into the first compartment 28, so that any part of the mixture carried up by the blades 46 will fall upon said deflector chute 50 and be discharged thereby away from the opening 34.

After the mixing operation has continued in the compartment 28 a sufficient period the plastic mixture is transferred to compartment 30 with a transfer chute 52 connected at its upper end to the upper part of the deflector chute 50 from 20 which it inclines in the opposite direction so that when the chutes 50 and 52 are moved backward to the dotted line position, Fig. 2, the mixture carried upward by the blades 46 will fall upon the chute 52 and be directed thereby into the 25 compartment 30 where the substances are further mixed by spiral-like blades 53 similar in shape and function to the blades 46.

The chutes 50 and 52 are fixed to a carrier 54 comprising a pair of bars 56 which extend longitudinally through the openings in the drum 6 and are pivotally connected at their rear ends to the lower ends of hangers 58, the upper ends of which are mounted upon a shaft 60 carried by a frame 62 fixed upon the truck 2. The forward ends of the bars 56 are pivotally connected to the lower ends of a pair of hangers 64 fixed at their upper ends upon an inner shaft 66 mounted in bearings 67 at upper forward portion of the frame 62. The shaft 66 is provided at one end with a fixed crank 68 pivotally secured at its free end to the upper end of a connecting-rod 70 which is pivotally secured at its lower end to a hand-lever 72 freely mounted upon a fulcrum 74 fixed to a sector 75 mounted upon the truck 2. With the foregoing arrangement it is apparent that when the hand-lever 72 is in the position shown by Fig. 1, the chutes 50 and 52 will be held in the full line position shown by Fig. 2, and when said hand-lever 72 is swung to the left, Fig. 1, the chutes 50 and 52 will be moved to the dotted line position, Fig. 2.

While the substances are being further mixed in the compartment 30 they are prevented by the parallel ends 55 of the blades 53 and a deflector 55

chute 76 from being carried outward prematurely through the opening 38. As shown by Fig. 2 the parallel ends 55 of the blades 53 adjoin the discharge end of the drum. The chute 76 is somewhat like the chute 50 but arranged to operate independently of the latter. As shown by Fig. 2, the chute 76 inclines downwardly from the outside to the inside of the compartment 30 and is attached at its upper end to a tiltable discharge chute 78 operably connected at its lower end by a hinge 80 to a mud hopper 82 secured to the frame 62 at a point below and outside of the opening 38. The chute 76 is further connected to the discharge chute 78 by one or more braces 84.

15 The tilting action of the discharge chute 78 is controlled by a pair of links 86 having pin-and-slot connections 88 with the upper end of said discharge chute 78 and fixed at their upper ends to an outer or tubular shaft 90 freely mounted upon the inner shaft 66 and provided at one end with a fixed crank 93, Fig. 1, pivotally secured at its free end to a connecting rod 94 pivoted at its lower end to a hand-lever 96 which may be freely mounted upon the fulcrum 74 or another one in axial alignment therewith. The foregoing arrangement of the hand-levers 72 and 96 places them close together and within easy reach of the operator. From the foregoing it is obvious that when the hand-lever 96 is in the position shown by Fig. 1, the chute 76 will occupy the active position disclosed by Fig. 2, but when said hand-lever 96 is shifted to the left the discharge chute 78 will be swung to an inclined position with its upper end within the opening 38 to receive the plastic mixture in order to discharge it into the hopper 82.

20 As the batch is discharged into hopper 82 it gravitates into one or more barrels 98, from which it is forced to the point of use by plungers 103 through pipes 100, valves 102, a manifold 104, and a hose 106.

25 Briefly the operation is as follows: Soil thrown into chute 40 is fed thereby into the first compartment 28 of drum 6 into which water is admitted from the tank 42 through the valve-controlled pipe 44. After partially mixing the soil and water the mixture is transferred to the second compartment 30 by shifting the chutes 50 and 52 to the dotted line position, Fig. 2, which operation is accomplished by shifting lever 72 to the left, Fig. 1. On completion of the mixing operation in compartment 30, lever 96 is shifted to the left, Fig. 1, to swing the upper end of discharge chute 78 into the compartment 30. The chute 78 then discharges the mixture into hopper 82 from which it gravitates into the barrels 98. The plungers 103 force the mixture outwardly through pipes 100, valves 102, manifold 104, and hose 106 the free end of which is inserted in a hole cut through a depression in the concrete beneath which the mixture is forced until the depressed portion of the concrete is raised to its original level.

30 From the foregoing description taken in connection with the drawings it is apparent that I have provided a mixing drum well adapted for the purpose intended, and while I have shown one form of the invention I reserve all rights to such other forms and modifications thereof as properly fall within the spirit and scope of the invention as claimed.

35 Having thus described my invention, what I claim and desire to secure by Letters Patent is:

1. In a machine of the character described, a rotary mixing drum having inlet and discharge openings and divided into a plurality of compartments, a chute for transferring a mixture from one compartment to another, a carrier extending longitudinally through the drum and to which said chute is fixed, and means arranged exteriorly of the drum for shifting said carrier longitudinally to alternately carry the chute to active and inactive positions. 5

2. In a machine of the character described, a rotary mixing drum having inlet and discharge openings and divided into a plurality of compartments, a chute for transferring a mixture from one compartment to another, a carrier extending longitudinally through the drum and to which said chute is fixed, a frame associated with the mixing drum, shafts supported by said frame, hangers depending from one of said shafts and operably connected to one end of the carrier, 15 hangers fixed to the other shaft and operably connected to the other end of the carrier, a crank fixed to the last-mentioned shaft to rock the same and thereby effect the movement of the chute to active and inactive positions, and manually controlled means for actuating said crank. 20

3. In a machine of the character described, a rotary mixing drum having inlet and discharge openings, a partition having an opening and dividing said drum into a receiving and mixing compartment and a mixing and delivery compartment, spiral-like blades in the interior of the first compartment adapted to mix substances and feed the mixture towards the partition, said blades having ends adjoining the partition and arranged in parallelism with the axis of the drum to avoid discharging the mixture into the second compartment, an inclined deflector chute arranged to partially enter the second compartment through the opening in the partition and 30 coact with the parallel ends of the blades in retaining the mixture in the first compartment, a transfer chute arranged adjacent to said deflector chute and inclined in an opposite direction thereto, said transfer chute being arranged to 35 partially enter the opening in the partition and transfer the mixture from the first compartment to the second compartment, means for shifting the deflector and delivery chutes so that the upper portion of either may be positioned in the partition opening, and blades in the second compartment adapted to feed the mixture towards the discharge opening of the drum. 40

4. In a machine of the character described, a rotary mixing drum having inlet and discharge openings, spiral-like blades mounted in said drum and adapted to mix substances and feed the mixture towards the discharge opening, said blades having parallel ends adjoining the end of the drum with the discharge opening and arranged in parallelism with the axis of the drum to avoid discharging the mixture through the discharge opening, an inclined deflector chute in the drum arranged to partially enter the discharge opening 65 and coact with the parallel ends of the blades in retaining the mixture in the drum, a discharge chute mounted adjacent to the discharge opening and adapted to be inclined until its upper end enters the discharge opening to receive the mixture and discharge it from the drum, and independent means for shifting the chutes to active and inactive positions. 70
